UNITED STATES PATENT OFFICE.

WILLIAM H. MILLSPAUGH, OF SANDUSKY, OHIO, ASSIGNOR TO SANDUSKY FOUNDRY & MACHINE CO., OF SANDUSKY, OHIO, A CORPORATION OF OHIO.

CENTRIFUGAL CASTING MACHINE.

Application filed January 27, 1923. Serial No. 615,222.

To all whom it may concern:

Be it known that I, WILLIAM H. MILLSPAUGH, a citizen of the United States, and a resident of Sandusky, county of Erie, and State of Ohio, have invented certain new and useful Improvements in Centrifugal Casting Machines, of which the following is a specification.

This invention relates to centrifugal casting machines and particularly to means for feeding molten metal in such machines.

In certain types of centrifugal casting machines it has been found desirable to pour the metal into the mold gradually from one end to the other of the mold. This method of pouring the metal permits air to escape from the mold and prevents air pockets or blow holes in the casting. This method has been accomplished by moving the pouring trough longitudinally of the mold as the metal is being poured.

This invention has for its object to provide means whereby molten metal can be poured into a centrifugal casting machine mold gradually from one end to the other thereof without imparting relative longitudinal movement to the mold or to the pouring trough.

Further objects of the invention will appear from the following description taken in connection with the drawings which form a part of this application and in which,

Fig. 1 is a longitudinal sectional elevation of a centrifugal casting machine constructed in accordance with the invention.

Fig. 2 is an end elevation of the left hand end of the construction shown in Fig. 1.

Fig. 3 is a transverse sectional elevation taken substantially on line 3-3 of Fig. 1, and

Fig. 4 is a plan view of the pouring trough illustrated in Fig. 1.

The invention briefly described consists in a centrifugal casting machine comprising a cylindrical mold and a pouring trough extending through and disposed in the mold and having therein a discharge opening extending longitudinally thereof and so constructed that when the trough is rotated the molten metal will be discharged into the mold gradually from one end of the trough to the other thereof. In the particular form of the invention illustrated the discharge opening in the trough is curved longitudinally and extends partially around the

trough, one end of the opening being angularly displaced from the other end thereof. This discharge opening may take the form of a spiral slot as illustrated in Fig. 4.

Referring to the drawings the centrifugal casting machine comprises a cylinder 10 rotatably mounted in rollers 11 journaled in suitable bearings 13 supported in uprights or standards 14. The cylinder 10 may be rotated in any desired manner and in the form of the invention illustrated a ring gear 15 is secured to the cylinder intermediate its ends. This gear is adapted to be driven from any suitable source of power to enable the cylinder to be rotated at the desired rate of speed.

The mold may be of any desired shape and in the form of the invention shown the cylinder 10 is shaped to cast a pipe having a flange at one end formed in a recess 16.

The ends of the cylinder have secured thereto plates 17 and 18 which may be bolted thereto as shown at 19.

A pouring trough 20 is used for introducing the molten metal into the cylinder. This trough is preferably made in the form of a circular or cylindrical pipe which as illustrated in the drawings at 21 is closed at both ends. The trough 21 preferably extends through the cylinder 10 and has its outer ends rotatably supported in bearings 22 and 23. The bearing 22 is shown in Fig. 2 as pivoted to standards or supports 24 to permit the bearing 22 to be swung downwardly when the casting is withdrawn from the cylinder. The bearing 23 is shown as fixedly supported on an upright or standard 25. An additional standard 26 having a bearing 27 at its outer end is provided for the purpose of supporting the end 28 of the trough when the trough is moved lengthwise in the cylinder after the casting has been made and to permit the casting to be withdrawn from the cylinder.

The trough may be rotated in any desired manner as by a handle 29 secured to a shaft 30 which in turn is secured to the end 28 of the trough. A feed hole or feed spout 31 is preferably formed on or secured to the trough in the position shown in Fig. 1 to facilitate pouring the molten metal into the trough.

As illustrated in Figs. 1 and 4 the trough 20 has formed therein a longitudinally extending discharge opening extending par-

tially around the circumference of the trough and being curved throughout its length preferably in the form of a spiral. From the showing in Fig. 4 it will be noted that the end 33 of the opening 32 is angularly displaced from the end 34 thereof. Because of this fact it will be evident that when the trough 20 is rotated to discharge the molten metal into the mold the metal 10 will first be discharged from the end 33 and will be gradually discharged from this end, to the end 34 as the trough is rotated. It will thus be evident that means has been provided for gradually discharging molten 15 metal into a mold from one end of the mold to the other end without necessitating the longitudinal movement of the trough relative to the mold or of the mold relative to the trough.

20 Although one specific embodiment of the invention has been particularly illustrated and described it will be understood that the invention is capable of modification and that changes in the construction and in the arrangement of the various cooperating parts 25 may be made without departing from the spirit or scope of the invention as expressed in the following claims.

What I claim is:—

30 1. A centrifugal casting machine comprising a cylinder, a trough rotatably mounted

therein and having a discharge opening therein, curved longitudinally from end to end.

2. A centrifugal casting machine comprising a cylinder, a trough rotatably mounted therein and having a discharge opening therein extending longitudinally of and partially around the trough all portions of said opening being angularly disposed 35 with relation to the axis of the cylinder.

3. A centrifugal casting machine comprising a cylinder, a trough rotatably mounted therein and having a discharge opening therein, extending longitudinally 40 thereof and substantially spirally around a portion of the circumference thereof.

4. A centrifugal casting machine comprising a cylinder, a trough rotatable therein and having a longitudinally extending curved discharge opening therein, the ends of said opening being angularly 45 displaced relative to each other.

5. A rotatable trough for centrifugal casting machines having a discharge opening angularly disposed throughout its length 50 with relation to the axis of rotation of the trough.

In witness whereof, I have hereunto set my hand this 23rd day of Jan., 1923.

WILLIAM H. MILLSPAUGH.

- tially around the circumference of the trough and being curved throughout its length preferably in the form of a spiral. From the showing in Fig. 4 it will be noted that the end 33 of the opening 32 is angularly displaced from the end 34 thereof. Because of this fact it will be evident that when the trough 20 is rotated to discharge the molten metal into the mold the metal will first be discharged from the end 33 and will be gradually discharged from this end to the end 34 as the trough is rotated. It will thus be evident that means has been provided for gradually discharging molten metal into a mold from one end of the mold to the other end without necessitating the longitudinal movement of the trough relative to the mold or of the mold relative to the trough.
- 20 Although one specific embodiment of the invention has been particularly illustrated and described it will be understood that the invention is capable of modification and that changes in the construction and in the arrangement of the various cooperating parts may be made without departing from the spirit or scope of the invention as expressed in the following claims.
- What I claim is:—
- 20 1. A centrifugal casting machine comprising a cylinder, a trough rotatably mounted
- therein and having a discharge opening therein, curved longitudinally from end to end.
2. A centrifugal casting machine comprising a cylinder, a trough rotatably mounted therein and having a discharge opening therein extending longitudinally of and partially around the trough all portions of said opening being angularly disposed with relation to the axis of the cylinder.
3. A centrifugal casting machine comprising a cylinder, a trough rotatably mounted therein and having a discharge opening therein, extending longitudinally thereof and substantially spirally around a portion of the circumference thereof.
4. A centrifugal casting machine comprising a cylinder, a trough rotatable therein and having a longitudinally extending curved discharge opening therein, the ends of said opening being angularly displaced relative to each other.
5. A rotatable trough for centrifugal casting machines having a discharge opening angularly disposed throughout its length with relation to the axis of rotation of the trough.

In witness whereof, I have hereunto set my hand this 23rd day of Jan., 1923.

WILLIAM H. MILLSPAUGH.

Certificate of Correction.

It is hereby certified that the name of the assignee in Letters Patent No. 1,533,202, granted April 14, 1925, upon the application of William H. Millspaugh, of Sandusky, Ohio, for an improvement in "Centrifugal Casting Machines," was erroneously described and specified as "Sandusky Foundry & Machine Co.," whereas said name should have been described and specified as *The Paper & Textile Machinery Company*, as shown by the records of assignments in this office; and that the said Letters Patent should be read with this correction therein that the same may conform to the record of the case in the Patent Office.

Signed and sealed this 12th day of May, A. D. 1925.

[SEAL.]

KARL FENNING,
Acting Commissioner of Patents.
